UNITED STATES PATENT OFFICE.

JOHN PORTER, OF JEFFERSON, TEXAS.

STEAM-BOILER.

Specification of Letters Patent No. 31,620, dated March 5, 1861.

To all whom it may concern:

Be it known that I, JOHN PORTER, of Jefferson, in the county of Marion and State of Texas, have invented a new and useful Improvement in Steam-Boilers; and I do hereby declare that the following is a full, clear, and exact description of the same, reference being had to the accompanying drawings, forming part of this specification, in which—

10 Figure 1 is a longitudinal vertical section of a boiler with my improvement. Fig. 2 is a transverse vertical section of the same in the plane indicated by the line α , α , in Fig. 1. Fig. 3 is a horizontal section of the 15 same, through the upper flues. Fig. 4 is a longitudinal vertical section of the fire-box detached.

Similar letters of reference indicate corresponding parts in the several figures.

20 My invention consists in a detachable fire-box constructed and applied in combination with the body of the boiler in the manner hereinafter described whereby I obtain a portable boiler which may be made of large 25 capacity, is easily set, is little liable to get out of repair, and is a very effective steam-generator.

To enable others skilled in the art to make and use my invention I will proceed to describe its construction and operation.

A represents the body of the boiler made separate from the fire-box, like an ordinary horizontal cylinder boiler. It may have any arrangement of flues that may be desired, 35 though represented with two lower horizontal flues a , a , and three upper horizontal flues b , b , b .

B C C D E, is the detachable fire box made entirely of boiler plate and double, so 40 that it contains a water space in every part. The lower part, which contains the grate G, is of quadrangular form in its horizontal section. The front B, is upright and so is the part D, which constitutes the fire-bridge, 45 and both these parts are hollowed out for the reception of the body A, of the boiler which rests directly upon the part B, and upon raised bearings c , c , so provided on or behind the part D, as to admit of the escape 50 of the products of combustion under the rear portion of the body. The sides C, C, which extend upward to within a short distance of the level of the top of the body A, are curved as shown in Figs. 2 and 4, to corre-

spond with the body of the boiler, and leave 55 spaces d , d , see Fig. 2, between them and the body. From the part D, the part E, extends in the form of an inverted arc under the body of the boiler to the rear end thereof, the sides of the said part E, corresponding 60 in form, and forming a continuation of the upper parts of the sides C, C, and the space d , d , e , between it and the sides and bottom of the body being sufficient for the circulation of the products of combustion. 65 The part E, may however be omitted, and the fire-box terminate at D, in which case the place of E, will have to be supplied by the setting of the boiler.

When the part E, is used the only setting 70 absolutely necessary will be at the extreme rear of the boiler to form a smoke chamber or breeching F, establishing communication from the space d , d , e , to the flues a , a , as the lower and front part of the fire-box may 75 rest upon the ground or upon a floor or deck. The space d , d , is covered at the top with plates f , f , dropped on to suitable resting places provided on the fire-box and boiler, and the whole or a portion of the upper part 80 of the boiler above these plates may be covered with brickwork or any non-conducting material. The connection between the flues a , a , and b , b , is made in front of the boiler by a breeching I, in the usual manner, and 85 the flues b , b , are connected in rear with the chimney J, by a breeching K. The water space of the fire-box is connected with the body of the boiler by a pipe L, arranged outside and in front, as shown in Fig. 1, or 90 in any other suitable manner. The feed pipe g, is connected with the rear end of the fire box, and a blow-off pipe h, is attached to the bottom of the part D, which is extended a little below any other part of the 95 fire-box to form a sediment well out of the circulation.

The fire-box constructed, as described and represented, with the part E, extending to the rear of the boiler, will be of about the 100 same weight as the body of the boiler, so that in the transportation of the boiler the body may be conveyed on one wagon, and the fire-box on another. In two ordinary cotton wagons a boiler of this kind, of from 105 fifteen to twenty horse power, may be conveyed into the woods without difficulty, while a boiler of the same capacity of any

ordinary construction requires a wagon or truck of particular construction for its transportation.

The circulation from the furnace to the chimney is indicated in Fig. 1, by red arrows, and it will be understood by reference to the drawing that every part of the interior of the fire-box is a heating surface.

I do not confine myself to any particular construction of or arrangement of the flues in the body of the boiler, but

What I claim as my invention, and desire to secure by Letters Patent, is—

The detachable fire-box, constructed of the form, and applied in combination with the body of the boiler, substantially as herein described.

JOHN PORTER.
